UNITED STATES PATENT OFFICE.

LUIS SMITH, OF CARETTA, WEST VIRGINIA.

MINER'S-LAMP-CARRYING MEANS.

1,257,087.

Specification of Letters Patent. Patented Feb. 19, 1918.

Application filed May 24, 1917. Serial No. 170,584.

To all whom it may concern:

Be it known that I, LUIS SMITH, a subject of the King of Hungary, resident of Carettta, county of McDowell, and State of West Virginia, have invented certain new and useful Improvements in Miners'-Lamp-Carrying Means, of which the following is a specification.

This invention relates to improvements in miners' lamp carrying means, and has as its special object the provision of means whereby a lamp of ordinary safety type may be securely attached to the cap or head covering of a person.

A further object is to provide such means in forms which may be readily attached to caps of the ordinary style, and whereby the lamp may be secured or released in an expeditious, safe and easy manner.

These and other like objects are attained by the novel construction and combination of parts hereafter described and shown in the accompanying drawings, forming a material part of this disclosure, and in which:—

Figure 1 is a perspective view showing an ordinary type of miner's lamp and its attachment to a cap such as is worn by miners.

Fig. 2 is a partial side elevational and sectional view of the same.

Fig. 3 is a fragmentary transverse sectional view taken on line 3—3 of Fig. 2.

Fig. 4 is a similar sectional view taken on line 4—4 of Fig. 2.

Fig. 5 is a front elevational view of the attachment showing the manner of disengaging the lamp.

Fig. 6 is a top plan view of the attachment, and

Fig. 7 is a bottom plan view of the same.

Figs. 1 and 2 show the crown 10 of the cap formed with a cylindrical body portion 11, to which is attached the visor 12, the whole being of the usual type of construction, as is also that of the lamp 15, provided with a base 16, top 17 and lens holder 18.

The invention consists of a supporting frame 20, having an angularly turned, flange-like projection 21 at its bottom upon which the base 16 of the lamp is adapted to rest, and contains an elongated slot 22 of increased area at its upper end 23, in which are receivable the out-turned ends 25 of a resilient wire ring 26, adapted to engage the lower part of the lamp, and by

means of which it is held against the frame 20 when desired, or by raising the ring so that the extending ends 25 may pass through the enlarged opening 23, permits the lamp 60 to be removed.

Formed with the frame 20 is a horizontally turned element 27, containing a slot 28, across which is secured a transverse pin 29, the support element 27 being then turned 65 down at 30, and bent outwardly into an arm 31, secured by rivets 32 or the like to the crown 10 of the cap.

Passing through the arm 31 is a rod 35, having a knob 36 at its extreme lower end 70 and being encircled by a spring 37 so as to be held normally downward.

The upper end 38 of the rod 35 is turned horizontally and bent obliquely downward at 39, terminating in a hook 40 adapted to 75 pass through the loop 42, rigidly secured to the head 17 of the lamp.

Thus when the rod 35 is in a downward, normal position, it is held by the spring 37, the hook passing through the loop 42 engaging with the pin 29, firmly securing the lamp in place.

In order to further secure the base 16 of the lamp in position, a vertical plate 45 is formed arcuately and has an arm 46 secured 85 by rivets 48 to the visor 12, so that the lamp is held at three separate fixed points firmly in engagement with the cap.

When it is desired to remove the same, it is merely necessary to grasp the rod 38, 90 as indicated more particularly in Fig. 5, raising the same, so as to cause it to disengage with the pin 29 and pass up through the loop 42; at the same time, the resilient spring ring ends 25 are disengaged from the 95 slot 20, whereupon the lamp may be removed.

From the foregoing, it will be seen that a neat and practical device has been presented whereby the lamp may be directly 100 and firmly engaged with the cap.

Having thus described my invention, what I claim as new, and desire to secure by Letters Patent, is:—

1. In a device of the class described, the 105 combination with a cap and a lamp, of a looped eye secured to the upper portion of said lamp, a bracket attached to the crown of said cap, said bracket having a part engageable with the base of said lamp, a 110 hooked element slidable in said bracket engageable in said loop, and means for nor-

mally holding said hook in engagement therewith.

2. In a device of the class described, the combination with a cap and a lamp, of a bracket rigidly secured to said cap, said bracket containing an elongated slot having an enlarged upper end, a resilient ring encircling said lamp having turned ends adapted to engage in the mentioned slot, a

loop on said lamp, a hooked element slidably engaged in said bracket, means for engaging said hooked element in said loop, and means permitting the disengagement of said hook from said loop. 10

In testimony whereof I have affixed my 15
signature.

LUIS SMITH.
